UNITED STATES PATENT OFFICE.

ANDREW GERMEEK, OF KINGSTON, PENNSYLVANIA.

DUMP-CAR-DOOR LOCK.

Application filed September 2, 1926. Serial No. 133,237.

The invention relates to improvements in locking means for the downwardly swingable doors mounted at the bottoms of dump pockets of railway cars commonly used for hauling stone, coal, gravel and the like.

It is the object of the invention to provide a new and improved door locking means in which novel provision is made for tightly forcing the door closed, for holding it in closed position, and for quickly releasing the door when the pocket is to be dumped.

With the foregoing in view, the invention resides in the novel subject matter herein-after described and claimed, the description being supplemented by the accompanying drawings.

Figure 1 is a side elevation showing the application of the invention, the door of a dump pocket being held in closed position by such invention, in this view.

Figure 2 is a horizontal sectional view on line 2—2 of Figure 1.

Figure 3 is an elevation as indicated by line 3—3 of Figure 1.

Figure 4 is an enlarged side elevation showing the manner of releasing the locking means to permit opening of the door.

Figure 5 is a detail horizontal section on line 5—5 of Figure 4.

Figure 6 is a perspective view of the bracket upon which all movable parts are mounted.

Figure 7 is a perspective view of the shaft upon which the door locking wheel and the ratchet wheel, yet to be described, are secured.

The construction herein disclosed may be considered as preferred and while this construction will be rather specifically described, it is to be understood at the outset, that within the scope of the invention as claimed, numerous variations may be made.

The numerals 8 and 9 designate two flat substantially horizontal arms disposed in spaced parallel relation and having attaching plates 10 and 11 at one end, the arm 9 being offset near its end as indicated at 12, to dispose its attaching plate 11 in contact with the plate 10. These plates are formed with aligned openings to receive rivets 13 or other fasteners, for securing the bracket structure (formed by the parts so far dealt with) to the exterior of one of the dump pockets P of a dump car. D designates the

usual downwardly swingable door of the pocket.

The free ends of the arms 8 and 9 are formed with axially aligned openings 14 whose common axis is at right angles to the plane of the plates 10 and 11. In these openings, a short, heavy shaft 15 is rotatably mounted, the outer end of this shaft being provided with projecting studs 16 for engagement with a suitable bar so that the shaft may be forcibly rotated in one direction, and this rotation will effect tight, final closing of the door D, as will hereinafter appear.

The outer ends of the studs 16 are formed with heads 17, and at the inner end of these studs, the shaft 15 is provided with cams 18. These cams effect outward forcing of the above named bar as it is being operated to turn the shaft and so wedge said bar against the heads 17, as to prevent slippage thereof.

A door-locking wheel 19 and a ratchet wheel 20 are fixedly secured to the shaft 15, by a key 21 and appropriate key-ways 22, or by other desired means. The wheel 19 is provided with a plurality of circumferentially spaced, peripheral teeth 23 which are adapted to engage the projecting end of a bar B, secured to the door D, as will be clear from Figures 1 and 4. After initial engagement of the bar end with teeth of the wheel 19, rotation of this wheel in the proper direction will cause tight closing of the door D. A suitable dog 24 is carried by the bracket structure and cooperates with the ratchet wheel 20 in holding the wheel 19 against retrograde rotation, so as to cause said wheel to tightly lock the door in closed position. Preferably, a pivoted safety lock 25 is provided to secure the dog 24 in operative position after final closing of the door D. In the present disclosure, the arm 9 is formed with an upwardly projecting lug 26 upon which the dog and the safety lock are pivoted, the pivots of these parts are being designated 27 and 28 respectively.

The free end of the dog 24 is provided with a projecting headed stud 29 to be engaged by a bar which is shown by the dotted lines 30 in Figure 4. The arm 9 is provided with an appropriate shoulder 31 to engage the inner end of this bar so that the latter may be effectively used as a lever to release the dog 24, after first releasing the safety

lock 25. Upon release of this dog, the weight resting upon the door D, will downwardly swing the latter and the wheel 19 will then rotate idly. When the door is to be again closed, it is upwardly swung by hand till the bar B engages the teeth of the wheel 19. Then, by means of the bar 30 or some other appropriate bar, engaged with the studs 16, the shaft 15 and its wheels 19 and 20 may be rotated. During this rotation, the teeth of the wheel 19, being engaged with the bar B, effect tight closing of the door D, and the dog 24 and ratchet wheel come into play to hold said wheel 19 against retrograde movement, so that the door will be effectively held in locked position.

The improved locking means is by preference applied to both sides of the pocket P and both ends of the bar B then project to engage the teeth of the door locking wheels. The ends of this bar preferably have openings O in which the bar 30 or some other bar may be carried, with its ends projecting to form handles, as seen in dotted lines in Fig. 3. These handles are often of assistance in swinging the door into engagement with the wheel 19.

The invention is simple and inexpensive, may be quickly and easily installed, and will be highly efficient and desirable. On account of the existing advantages for the structural features which I have disclosed, they will in most instances be followed. However, as stated, variations may be made within the scope of the invention as claimed.

I claim:—

1. A locking means for a dump car door, comprising a bracket for attachment to the exterior of a dump pocket of a car, a door-locking wheel mounted on said bracket, said wheel having peripheral teeth to engage a portion of a door of said pocket and force the door tightly closed when said wheel is turned in one direction, means whereby said wheel may be so turned, a ratchet wheel rotatable bodily with said door-locking wheel, and a dog mounted on said bracket, said dog and ratchet wheel being cooperable in holding the door-locking wheel against retrograde turning until the car is to be dumped.

2. A locking means for a dump car door, comprising a bracket having a portion disposed in a vertical plane for mounting against the exterior of a dump pocket of a

car, said bracket having two horizontally spaced arms projecting from said vertical portion and formed with alined bearing openings whose common axis is at right angles to the aforesaid plane, a short shaft passing through said bearing openings and provided at its outer end with means whereby it may be rotated, a door-locking wheel fixedly mounted on said shaft between said arms, said arms having peripheral teeth to engage a portion of a door of said pocket and force the door tightly closed when the shaft is rotated in one direction, a ratchet wheel secured on said shaft, and a dog mounted on one of said arms and cooperable with said ratchet wheel to hold said door-locking wheel against retrograde rotation until the car is to be dumped.

3. A locking means for a dump car door, comprising two parallel arms having attaching plates at one end, one of said arms being offset between its ends to position its attaching plate in contact with the plate of the other arm, said plates having openings to receive fasteners for securing them against the exterior of a dump car pocket, the free ends of said arms having alined bearing openings, a short shaft passing through said bearing openings and provided at its outer end with means whereby it may be rotated, a door-locking wheel fixedly mounted on said shaft between said arms, said arms having peripheral teeth to engage a portion of a door of said pocket and force the door tightly closed when the shaft is rotated in one direction, a ratchet wheel secured on said shaft, and a dog mounted on one of said arms and cooperable with said ratchet wheel to hold said door-locking wheel against retrograde rotation until the car is to be dumped.

4. In a locking means for a dump car door, a door-locking wheel, a short shaft by which it is carried, studs projecting outwardly from one end of said shaft and having heads at their outer ends, and cams on the shaft at the inner ends of said studs, said studs being adapted for engagement by a bar used to rotate the shaft, said cams serving to force the bar outwardly toward said heads.

In testimony whereof I have hereunto affixed my signature.

ANDREW GERMEK.
